UNITED STATES. PATENT OFFICE.

FREDERICK B. THATCHER, OF BRIDGEPORT, CONNECTICUT, ASSIGNOR, BY MESNE ASSIGNMENTS, TO THE AETNA STOPPER COMPANY, OF PAWTUCKET, RHODE ISLAND.

ATTACHMENT FOR BOTTLING-MACHINES.

SPECIFICATION forming part of Letters Patent No. 352,165, dated November 9, 1886.

Application filed January 17, 1884. Serial No. 117,826. (No model.)

To all whom it may concern:

Be it known that I, FREDERICK B. THATCHER, of Bridgeport, in the county of Fairfield and State of Connecticut, have invented certain new and useful Improvements in Attachments for Bottling-Machines; and I do hereby declare that the following is a full, clear, and exact description thereof, whereby a person skilled in the art can make and use the same, reference being had to the accompanying drawings, and to the letters of reference marked thereon.

Like letters in the figures indicate the same parts.

15 Figure 1 is a view in elevation of part of a bottle-filling machine, showing the head in section and the feed-pipe bearing the valves. Fig. 2 is a view in horizontal central section of the filling-pipe and valves, and a vertical 20 central section of the head, showing the relative position of the parts when filling a bottle. Fig. 3 is a similar sectional view of the same parts, with the parts in position for the escape of compressed air. Fig. 4 is a view in cross-section on plane denoted by line xx of Fig. 3.

My invention, as herein illustrated, relates more particularly to the class of bottle-filling devices used to fill a bottle that has a stopper or valve closed by the outward pressure of the 30 gas contained in the bottle. A bottle-stopper of this class is described in the United States Patent No. 283,436, dated August 21, 1883; and my present invention is especially useful in combination with the device therein shown.

35 My invention consists in the combination, with a chambered head having an inlet and an outlet, the outlet being provided with a projecting stem to open an outwardly-closing valve in the vessel, the said stem being slabbed 40 off longitudinally to permit the passage thereby of liquid and gas, of a filling-tube connected with the inlet to said chambered head, provided with a stop-valve and a stop-and-vent valve, the said stop-and-vent valve being located between the chambered head and the 45 stop-valve, and adapted to open the fluid-passage and close the air-vent, whereby the operation of permitting the escape of compressed gas from the vessel when partially filled and 50 the subsequent filling of the vessel with the

liquid under pressure may be performed in the manner and for the purposes to be herein-after fully explained.

In the accompanying drawings, the letter a denotes the cross-bar of the frame b of a bottle-filling machine of ordinary construction; c , a metallic head having a chamber, d , opening downward and on one side; e , a housing or packing held in place by nut f ; g , a stem slabbed off on one or more sides and threaded 55 on its edges to fit the threaded downward opening in the head, in which it is secured with its lower end projecting beyond the lower face of the housing.

In the lateral opening of the head the main 65 filling-tube h is secured, as by a thread fitting the threaded socket, and this tube bears the stop-valve i , of common form, and also the stop-and-vent valve k , of the class commonly used on water-pipes to stop the supply and drain 70 the portion of pipe that is above the cock or valve, the latter being located between the stop-valve and the head and as close as practicable to the head.

The filling-pipe leads from any usual source 75 of supply, and in filling bottles with liquids sweetened and flavored by sirups the stop-cock is usually combined with the sirup-pump; but the form shown may be used in filling bottles with mineral waters, plain soda, 80 and the like.

The bottle l , when ready to be filled, is placed on the stand below the head, with the stopper fastened down, as shown in the drawings, and in such position that the stem g , 85 when the housing bears upon the top of the bottle, will enter the central perforation in the stopper and thrust open the valves m in the elastic plug. When the bottle is thus held, the stop-valve i is opened and the liquid under 90 pressure passes through the main induct-passage, through the stop-and-vent valve, the head, along the sides of the stem, and into the bottle, which is filled to about two-thirds its capacity, at which point the compressed air 95 accumulates in the upper part of the bottle, and must be released before the bottle can be completely filled.

It may be well to state that bottles are filled with carbonated liquids, mineral waters, spark- 100

ling wines, and the like under pressures varying from thirty to one hundred pounds to the square inch, the average pressure on carbonated beverages being sixty to seventy pounds; 5 and it is very essential that the predetermined pressure shall be certainly given to the bottled liquid, as its life, sparkle, and quality depend on this. With my improved devices and method of filling this is insured, as the stop-and-vent valve is next closed as to the main passage, and at the same time the vent *k* is opened and the compressed air allowed to escape, as indicated by the arrows in Fig. 3. 10 This air-valve is opened and quickly closed again, the main passage being again opened by the same movement that closes the vent, and the filling of the bottle completed by the inpouring of the liquid under the whole pressure. As soon as the bottle is filled the stop- 15 valve is closed and the head lifted, which withdraws the stem and allows the valves *m* to close.

It will be seen that the last pressure upon the contents of the bottle was the same as that 20 in the main supply-tube and the source, and that the bottle is filled under the pressure indicated at the fountain or gage.

The main feature of my invention—the arrangement and use of the combined stop-and-

vent valve, whereby the bottle is filled to the required pressure—is obviously as applicable to the filling and corking machine as to the special class hereinbefore described.

I claim as my invention--

In an apparatus for filling bottles and other vessels to contain liquid under pressure, the combination, with a chambered head having an inlet and an outlet, the outlet being provided with a projecting stem to open an outwardly-closing valve in the vessel to be filled, 40 the said projecting stem being slabbed off longitudinally to permit the passage thereby of liquid or gas, of a filling-tube connected with the inlet to said chambered head, provided with a stop-valve and a stop-and-vent 45 valve, the said stop-and-vent valve being adapted to open the fluid-passage and close the air or gas vent, whereby the operation of permitting the escape of compressed gas from the vessel when partially filled, and the subsequent filling of the vessel with the liquid under pressure, may be performed substantially in the manner and for the purpose hereinbefore set forth.

FREDERICK B. THATCHER.
